UNITED STATES PATENT OFFICE.

EDWARD WADE, OF NORWICH, CONNECTICUT.

PUMP.

Specification of Letters Patent No. 28,704, dated June 12, 1860.

To all whom it may concern:

Be it known that I, EDWARD WADE, of Norwich, in the county of New London and State of Connecticut, have invented a new 5 and improved Motion for Pumps and other Machines; and I do hereby declare that the following is a full, clear, and exact description of the same, reference being had to the accompanying drawing, forming a part of 10 this specification, in which—

Figure 1 represents a vertical central section of my invention. Fig. 2 is a horizontal section of ditto, the line x, x , Fig. 1, indicating the plane of section.

15 Similar letters of reference in both views indicate corresponding parts.

This invention consists in the arrangement of a horizontally rotating cam disk, in combination with a rising and falling yoke, 20 and with a series of lazy tongs in such a manner that by rotating the disk a rapid reciprocating motion is imparted to a pump piston or other part of a machine attached to the extreme end of the lazy tongs.

25 To enable others skilled in the art to make and use my invention I will proceed to describe its construction and operation with reference to the drawing.

A represents a disk provided with a cam 30 groove a , and attached to a vertical arbor B. This arbor has its bearings in a frame C, which is firmly secured to the top of a pump barrel D, or to any other convenient place, and it (the arbor) is rotated by means 35 of a series of levers E, inserted into sockets b , on the top end of the arbor or in a plate c , attached to said top end.

The cam groove a , forms the guide for friction rollers d , that are secured to the 40 upper ends of arms e , which projects from the yoke F, and the shape of the cam groove is such that on rotating the disk A, the yoke is caused to rise and fall several times, for each revolution of the disk. The cam groove 45 represented in the drawing, is furnished with four projections a' , forming a uniform wave line and causing the friction rollers on the ends of the arms e , to rise and fall

four times, but it will be easily understood that the number and also the form of said 50 projections may be changed to suit circumstances.

The yoke F, connects by means of bars g , with the pivot h , which connects the centers of the second pair of links i , of a series 55 of lazy tongs G, but instead of connecting said bars with the central pivot h , of the second link, two pairs of such bars might be employed and connected to the pivots h' , which unite the ends of the first and the 60 second link, and the effect of my machine would be considerably improved.

The pivot i , which unites the ends of the bars constituting the first link of the lazy tongs passes through a bracket H, secured to 65 the center of the bottom plate of the frame C, so that by moving the yoke F, up and down, the whole series of lazy tongs are extended and contracted. It is obvious that the number of links constituting the series 70 of lazy tongs G, may be increased at pleasure, and a rising and falling, or a reciprocating motion can thereby be imparted to a pump piston attached to the extreme end of the lazy tongs, or said lazy tongs may be 75 connected to any other machine or part of a machine to which a reciprocating motion is to be imparted.

This invention can be applied however with particular advantage to pumps, and the 80 reciprocating motion imparted to the piston or plunger is very rapid and the stroke can be increased at pleasure, and the power necessary to operate the piston is very trifling.

Having thus fully described my invention, what I claim as new, and desire to secure by Letters Patent, is:—

The arrangement and combination of the horizontally rotating cam disk A, rising and falling yoke F, and series of lazy tongs 90 G, constructed and operating substantially in the manner and for the purpose specified.

EDWARD WADE.
